Primary Examiner — Dana L Meyrow(74) *Attorney, Agent, or Firm* — Charles T. J. Weigell, Esq.; Fross Zelnick Lehrman & Zisus, P.C.(57) **CLAIM**

The ornamental design for a bottle, as shown and described.

DESCRIPTION

FIG. 1 is a front perspective view of my new design; FIG. 2 is a front view of the bottle shown in FIG. 1, with the rear and side views being identical; and,

FIG. 3 is a top view of the bottle shown in FIG. 1.

The broken lines in the drawings showing the bottle pour spout illustrate the portions of the bottle that form no part of the claim.

The repeating dot pattern applied to the lower portion of the bottle is intended to represent contrasting appearance.
